UNITED STATES PATENT OFFICE

CHARLES BENJAMIN REDRUP, OF STOCKPORT, ENGLAND

ENGINE OR PUMP

Application filed July 18, 1930. Serial No. 378,446, and in Great Britain December 28, 1928.

This invention relates to engines, pumps and the like of the axial or wobbler type, that is of the type in which the axis of the crank-shaft is parallel to the direction of movement 5 of the piston or pistons, and the invention is concerned with engines or pumps of this type in which a wobbler is mounted on an inclined portion of the crank-shaft. In such engines or pumps the thrust of the pistons is transmitted to the wobbler with the result that the latter oscillates backwards and forwards and causes the crank-shaft to rotate. One of the objects of the present invention is to provide an extremely light and compact construction specially suitable for aircraft engines.

A further object is to provide an improved stabilizing or anchor member, transmitting the driving torque from the wobbler to the cylinder-assembly, which will occupy little space and will not involve any increase in the dimensions of the wobbler-casing, and which will be in balance about its axis of oscillation and have small moment of inertia about 25 that axis.

Further objects are to provide an improved wobbler which will be lighter and stiffer than those hitherto proposed, and to provide an improved universal-joint connection between the pistons and the wobbler.

In order that the invention may be clearly understood and readily carried into effect, one internal combustion engine constructed in accordance therewith will now be described 35 by way of example with reference to the accompanying drawings, in which

Figure 1 is a central cross-section through the engine;

Figure 2 is a section on the line II-II 40 of Figure 1, and

Figure 3 is a side view of the wobbler or star-member.

This engine, which is particularly designed for use in aeroplanes, comprises a 45 casing 1 within which a crank shaft 2 is mounted on roller and ball bearings 3. The crank shaft 2 is formed with an inclined portion 4 around which two sleeves 5 are placed between the ends of the inclined portion 4 and collars 6. A star-member 7,

formed in two halves on the line A-A (Figure 3) for convenience of assembly, is mounted upon the sleeves 5, the star-member being made hollow for the sake of lightness. A 55 number of cylinders 8 are mounted around and parallel to the crank shaft 2, each cylinder containing a piston 9 connected by a piston rod 10 to the end of one of the arms of the star member 7. The fuel and air mixture is admitted through an inlet passage 60 11 to a central manifold 12 arranged around the crank shaft 2, from which manifold passages 13 controlled by inlet valves 14 lead to the cylinders 8. Exhaust takes place through passages 15 controlled by valves 16. 65

A stabilizing member in the form of a hollow tapered rod 17 having a forked end is mounted in the engine casing 1 by means of a member 18 having a cylindrical bore constituting the bearing surface and a spherical exterior fitting within a seat having spherical surfaces. This seat is constituted in part by the casing 1 and in part by a cap 19 which is secured to the casing 1. As a result the stabilizing member 17 can oscillate freely 75 about its longitudinal axis, and slightly in every other sense, and can also slide slightly longitudinally. The forked end of the stabilizing member 7 is formed with projections 20 which fit within sockets 21 in the star 80 member 7, thus constituting trunnions carrying the star member 7. The axis of the trunnions is at right angles to the inclined portion 4 of the crank-shaft 2, and passes through its centre which is the point where 85 the axes of the crank-shaft 2 and the inclined portion 4 intersect.

It should be noted that, although in theory the un-forked end of the stabilizing member could be mounted in a plain cylindrical bearing, allowing angular oscillation of the stabilizing member about its longitudinal axis, the inevitable errors of manufacture make it desirable in practice to mount such cylindrical bearing in the engine casing or the like in a spherical housing as described above so as to prevent undue stresses being set up in the engine.

Each connecting rod 10 is connected to the 90 end of the appropriate arm of the star mem- 95

ber 7 by a joint comprising a pin 22 fitting in holes 23 in the arm and engaging in a circular groove in a pin 24 to which the end of the connecting rod 10 is pivoted. The two pins are held together by a connecting piece 25 and on account of the groove the pins 22 lock the pins 24 in position. This joint thus allows of relative motion between the connecting rod and the arm in two different planes. Each connecting rod 10 is connected to its piston 9 in a similar manner by pins 22 and 24.

Lubrication is effected by making the crank shaft 2 hollow and leading suitable pipes or passages 26 from the interior of the crank shaft up to the joints and along the connecting rods 10, the oil being of course fed under pressure to the hollow crank shaft.

In operation the force of the explosion in each cylinder is transmitted as a pure thrust along the connecting rod to the end of the arm of the star member 7. This star member is thus caused to oscillate about the trunnions 20, the star member 7 being shaped as shown in Figure 1 so as to clear the stabilizing member 17, this oscillation causing the crank shaft to rotate. A further oscillation of the star member 7 about the axis of the stabilizing member 17 follows, the member 17 oscillating in the member 18. Any tendency for the star member 7 to rotate with the crank-shaft is, however, prevented by the stabilizing member 17. There is, therefore, no risk of the whole mechanism jamming. It is a particular advantage of the invention that the greatest tendency for the end of the arm of the star member 7 to fall away from its path and, therefore, for the star member to rotate, comes at the middle of the stroke when the thrust on the end of the arm is not parallel to the inclined portion of the crank shaft. The thrust at the beginning of the stroke is directly parallel to the inclined portion of the crank shaft, so that any sudden stresses at the beginning of the stroke, due for example to pre-ignition, are not taken by the stabilizing member.

The invention is not, of course, limited to the particular embodiment shown and described; for example, it is applicable to pumps or compressors, and to engines other than internal-combustion engines, and also to engines, pumps or compressors in which the shaft is stationary and the cylinder assembly revolves around it.

I claim:—

1. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a central cavity extending around said

inclined portion, pistons reciprocable in said cylinders and connected to said wobbler, and a stabilizing member pivotally anchored to the cylinder-assembly, pivotally attached to the wobbler at a point within said cavity and lying substantially wholly within the periphery of the wobbler.

2. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a central cavity extending around said inclined portion, pistons reciprocable in said cylinders and connected to said wobbler, and a stabilizing member pivoted to the wobbler within said cavity at two points on opposite sides of the shaft about an axis transverse to said shaft and pivoted to the cylinder-assembly at a point displaced from said axis about an axis which is transverse to the shaft and to the aforesaid axis.

3. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and formed with a central cavity, pistons reciprocable in said cylinders and connected to said wobbler, and a stabilizing member pivoted to the wobbler within said cavity at two points on opposite sides of the shaft about an axis transverse to said shaft and pivoted to the cylinder-assembly at a point displaced from said axis about an axis which is transverse to the shaft and to the aforesaid axis and which contains the centre of gravity of the stabilizing member.

4. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a central cavity, pistons reciprocable in said cylinders and connected to said wobbler, and a stabilizing member pivoted to the wobbler within said cavity at two points on opposite sides of the shaft about an axis perpendicular to the inclined portion of said shaft and pivoted to the cylinder-assembly at a point displaced from said axis about an axis which is perpendicular to the shaft and to the aforesaid axis.

5. In combination, a shaft having an inclined portion, a cylinder-assembly comprising a plurality of cylinders parallel to said

shaft and spaced thereabout, said cylinder-assembly and said shaft constituting two elements one of which is rotatable with respect to the other, a wobbler rotatably mounted on the inclined portion of the shaft and having a central cavity, pistons reciprocable in said cylinders and connected to said wobbler, and a stabilizing member pivoted to the wobbler within said cavity at two points on opposite sides of the shaft about an axis perpendicular to the inclined portion of said shaft and pivoted to the cylinder-assembly at a point displaced from said axis about an axis which is perpendicular to the shaft and to the aforesaid axis and passes through the point of intersection of the axis of the shaft and the axis of the inclined portion thereof.

6. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a central cavity, pistons reciprocable in said cylinders and connected to said wobbler, and a stabilizing member pivoted to the wobbler within said cavity at two points on opposite sides of the shaft about an axis perpendicular to the inclined portion of said shaft and pivoted to the cylinder-assembly at a point displaced from said axis about an axis which is perpendicular to the shaft and to the aforesaid axis and passes through the point of intersection of the axis of the shaft and the axis of the inclined portion thereof and which contains the centre of gravity of the stabilizing member.

7. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a central cavity, pistons reciprocable in said cylinders and connected to said wobbler and a stabilizing member pivoted to the wobbler within said cavity at two points symmetrically disposed on opposite sides of the shaft about an axis perpendicular to the inclined portion of said shaft and passing through the point of intersection of the axes of said shaft and said inclined portion, and pivoted to the cylinder-assembly at a point displaced from said axis about an axis perpendicular to the shaft and passing through the aforesaid point of intersection.

8. In combination, a shaft having an inclined portion, a cylinder-assembly comprising a plurality of cylinders parallel to said shaft and spaced thereabout, said cylinder-

assembly and said shaft constituting two elements one of which is rotatable with respect to the other, a wobbler rotatably mounted on the inclined portion of the shaft and having a central cavity, pistons reciprocable in said cylinders and connected to said wobbler and a stabilizing member pivoted to the wobbler within said cavity at two points on opposite sides of the shaft about an axis perpendicular to the inclined portion of said shaft and passing through the point of intersection of the axes of said shaft and said inclined portion, and pivoted to the cylinder-assembly at a point displaced from said axis about an axis perpendicular to the shaft, passing through the aforesaid point of intersection and containing the centre of gravity of the stabilizing member.

9. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a cavity therein, pistons reciprocable in said cylinders and connected to said wobbler, and a stabilizing member lying substantially wholly within the periphery of said wobbler, pivoted to the wobbler within said cavity at two points on opposite sides of the shaft about an axis transverse to said shaft and pivoted to the cylinder-assembly at a point displaced from said axis about an axis which is transverse to the shaft and to the aforesaid axis.

10. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a cavity therein, pistons reciprocable in said cylinders and connected to said wobbler, and a stabilizing member pivoted to the wobbler within said cavity at two points on opposite sides of the shaft about an axis transverse to said shaft and pivotally anchored to the cylinder-assembly at a point displaced from said axis and situated on a line transverse to said axis and to said shaft.

11. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, a wobbler rotatably mounted on the inclined portion of the shaft and having a cavity therein, pistons reciprocable in said cylinders and connected to said wobbler and

5 a stabilizing member pivoted to the wobbler within said cavity at two points on opposite sides of the shaft about an axis perpendicular to the inclined portion of the shaft at the point of intersection of the axes of the shaft and its inclined portion and universally-jointed to the cylinder-assembly at a point displaced from said axis and situated on a line perpendicular thereto and passing through the aforesaid point of intersection.

10 12. In combination a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler connected to said pistons and rotatably mounted on the inclined portion of the shaft, said wobbler comprising two parts fitting together on a plane containing the axis of said inclined portion and detachably secured together and a stabilizing member anchored to the engine casing and to the interior of the wobbler.

15 13. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler connected to said pistons and rotatably mounted on the inclined portion of the shaft, said wobbler being of multi-arm shape and comprising two parts detachably secured together and fitting together on a plane containing the axis of said inclined portion and passing through one of the arms and a stabilizing member anchored to the engine casing and to the interior of the wobbler.

20 14. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler connected to said pistons and rotatably mounted on the inclined portion of the shaft, said wobbler comprising a hollow shell-like structure of double taper form and a stabilizing member anchored to the engine casing and to the interior of the wobbler.

25 15. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler connected to said pistons

and rotatably mounted on the inclined portion of the shaft, said wobbler comprising a multi-arm hollow shell-like structure of double taper form and a stabilizing member anchored to the engine casing and to the interior of the wobbler.

16. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler connected to said pistons and rotatably mounted on the inclined portion of the shaft, said wobbler comprising a hollow shell-like structure of double taper form in two parts detachably secured together and fitting together on a plane containing the axis of said inclined portion and a stabilizing member anchored to the engine casing and to the interior of the wobbler.

17. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, and a wobbler connected to said pistons and rotatably mounted on the inclined portion of the shaft, said wobbler including two axially-separated hub-portions and said inclined portion of the shaft having two pairs of shoulders one pair embracing one hub-portion and the other embracing the other hub-portion.

18. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler rotatably mounted on the inclined portion of the shaft, and connections between said pistons and said wobbler each constituted by a universal joint including two pivot-pins having their axes mutually perpendicular but not intersecting, one of said pivot-pins being recessed to fit the cylindrical surface of the other, a bearing member arranged to hold the two pivot-pins in contact with one another and a stabilizing member anchored to the engine casing and to the interior of the wobbler.

19. In combination, a shaft having an inclined portion, a cylinder-assembly comprising a plurality of cylinders parallel to said shaft and spaced thereabout, said cylinder-assembly and said shaft constituting two elements one of which is rotatable with respect to the other, pistons reciprocable in said cylinders, a wobbler rotatably mounted on the inclined portion of the shaft and con-

nected to the pistons, said wobbler having a central cavity extending around said inclined portion, and a stabilizing member pivotally attached to the wobbler at a point within said cavity and pivotally anchored to the cylinder-assembley.

20. In combination, a shaft having an inclined portion, a cylinder-assembley comprising a plurality of cylinders parallel to said shaft and spaced thereabout, said cylinder-assembley and said shaft constituting two elements one of which is rotatable with respect to the other, pistons reciproicable in said cylinders, a wobbler rotatably mounted on the inclined portion of the shaft and connected to the pistons, said wobbler having a central cavity extending around said inclined portion, and a stabilizing member pivotally attached to the wobbler at two points within said cavity on opposite sides of the inclined portion and pivotally anchored to the cylinder-assembley.

In witness whereof I hereunto subscribe my name this 5th day of July, 1929.
